UNITED STATES PATENT OFFICE.

J EDWARD GLOEKLER, OF PITTSBURGH, PENNSYLVANIA, ASSIGNOR TO BERNARD GLOEKLER COMPANY, OF PITTSBURGH, PENNSYLVANIA, A CORPORATION OF PENNSYLVANIA.

DESIGN FOR A REFRIGERATOR.

50,939.

Specification for Design. Patented June 19, 1917.

Application filed March 28, 1917. Serial No. 158,130. Term of patent 7 years.

To all whom it may concern:

Be it known that I, J EDWARD GLOEKLER, a citizen of the United States, residing at Pittsburgh, in the county of Allegheny and State of Pennsylvania, have invented a new, original, and ornamental Design for Refrigerators, of which the following is a specification, reference being had to the accompanying drawing, forming a part thereof.

The figure is a perspective view of a refrigerator, showing my new design.

I claim:

The ornamental design for a refrigerator, as shown.

J EDWARD GLOEKLER.
